J. H. STEVENS.

Fire-Alarm Telegraph.

No. 69,503.

Patented Oct. 1, 1867.

United States Patent Office.

J. HORACE STEVENS, OF BOSTON, MASSACHUSETTS.

Letters Patent No. 69,503, dated October 1, 1867.

IMPROVEMENT IN FIRE-ALARM TELEGRAPHS.

The Schedule referred to in these Letters Patent and making part of the same.

TO ALL WHOM IT MAY CONCERN:

Be it known that I, J. HORACE STEVENS, of Boston, in the county of Suffolk, and State of Massachusetts, have invented a new and useful Improvement in Fire-Alarm Telegraphs; and I do hereby declare that the following is a full, clear, and exact description of the construction and operation of the same, reference being had to the accompanying drawings, forming a part of this specification, in which—

Figure 1 represents a complete fire-alarm telegraph circuit, both office and out-of-door connections.

Figure 2 the lower or reversing side of the rheotrope, and

Figure 3 the upper side of the rheotrope.

My invention consists in so connecting an automatic signal-box, as now in use, with the circuit passing through the rheotrope at the central station, that the rheotrope will be started by the electric current, and the bells or gongs in the circuit will all be struck, as indicated by the breaks on the circuit-wheel of the signal-box, while at any desired time the rheotrope may be thrown out of the circuit, so that the line may be used or tested without ringing the bells or gongs.

In the drawings, A is the battery for working the circuit. B B are switches, which, in the position shown, send the current through the rheotrope, but, if moved to knobs C C, cut out the rheotrope connections. D is the rheotrope cylinder, to be moved by clock-work, or its equivalent, said clock-work being set in motion by start-magnet E, on the breaking and closing the circuit by signal-box K. F is a writing-key, G an office call-bell, H an office galvanometer. I is the combination of permanent magnet on a movable arm and reversible electro-magnets, operating the striking apparatus of bells and gongs. K is the automatic signal-box, and L L L are the springs of the rheotrope, connected by wires M with the switch-knobs, writing-key, start-magnet, and signal-box.

When the signal-box K is put in operation each break and closing of the circuit causes an operation of the start-magnet E, which allows the clock-work to revolve the rheotrope, and by means of the reversing-magnets at I delivers one stroke upon the bell or gong. But if we remove the switches B to knobs C the rheotrope connections are cut out of the circuit, and the signal-box may be put in operation, the key F used for writing, the lines tested for grounds, and all important operations carried on, without the possibility of letting off the bells or gongs, as these can only be struck by the operation and aid of a reversed current.

I claim as my invention, and desire to secure by Letters Patent—

1. The rheotrope D and reversing-magnets I, in combination with each other, when connected with and operated by signal-box K, substantially as described.
2. The arrangement and combination of the wires M M, switches B, and knobs C, so as to include in or exclude from the circuit the rheotrope D, substantially as and for the purpose described.
3. The described combination and arrangement of signal-box K, start-magnet E, rheotrope D, with its springs L and wires M, with switches B and reversing-magnet J, substantially as and for the purpose described,

J. H. STEVENS.
